UNITED STATES PATENT OFFICE

124,214

DESIGN FOR A COMBINED BURIAL CASKET
HANDLE AND ESCUTCHEONSHarold O. Utter, Richmond, Ind., assignor to P. R.
Dudley, Marion, Ohio

Application April 15, 1940, Serial No. 91,689

Term of patent 3½ years

To all whom it may concern:

Be it known that I, Harold O. Utter, a citizen of the United States, residing at Richmond, in the State of Indiana, have invented a new, original, and ornamental Design for a Combined Burial Casket Handle and Escutcheons, of which the following is a specification, reference being had to the accompanying drawings, forming part thereof.

In the drawings,

Figure 1 is a side elevational view of a combined burial casket handle and escutcheons, showing my new design;

Figure 2 is a fragmentary end elevational view of the design shown in Figure 1;

Fig. 3 is an enlarged front view of the corner escutcheons, shown in Figs. 1 and 2;

Fig. 4 is a similar side view of the same;
Fig. 5 is a similar end view of the same;
Fig. 6 is a bottom plan view thereof;
Fig. 7 is an enlarged front view of the side escutcheon shown in Fig. 1;
Fig. 8 is a side view and
Fig. 9 is a bottom plan view thereof.

It is understood that the handle and escutcheons extend entirely around the casket in the arrangement shown, the smaller central escutcheon appearing on the side being omitted at the ends of the casket.

I claim:

The ornamental design for a combined burial casket handle and escutcheons, substantially as shown and described.

HAROLD O. UTTER.
